UNITED STATES PATENT OFFICE.

OSCAR SCHLICHTER, OF HAMILTON, OHIO, ASSIGNOR TO KRAUTH & BENNINGHOFEN,
OF HAMILTON, OHIO, A FIRM.

MANIFOLDING MACHINE.

Application filed March 10, 1921. Serial No. 451,225.

To all whom it may concern:

Be it known that I, OSCAR SCHLICHTER, a citizen of the United States, and residing at Hamilton, in the county of Butler and 5 State of Ohio, have invented a new and useful Improvement in Manifolding Machines, of which the following specification is a full disclosure.

My invention relates to improvements in 10 autographic registers or manifolding machines, in which mechanical feeding means is employed for advancing the web of paper or several superposed webs over the writing table of the machine for rewinding one of 15 the webs upon a rewinding spindle within the frame of the machine.

The machine is adapted to operate upon webs of paper which have successive symbols or printed forms thereupon and said 20 webs are provided with perforations having relation to said symbols or forms, and of definite spacing lengths longitudinally of the webs. A plurality of such perforated webs in a superposed relation are employed 25 for manifolding purposes and the perforations of the several webs are arranged for registration. The longitudinal spacing of the perforations however, for various uses 30 may vary relatively, and for the machine shown herein known as a "record" or "summary" machine, the longitudinal spacing of the record web, which is rewound within the machine, is considerably less than the webs which are issued from the machine.

35 The mechanism of the machine is designed for translating or feeding the webs in regulated distance or premeasured lengths governed by the distance of the longitudinal aperture spacing of the web or webs 40 employed for successive advancement of the webs, and the registry of the perforations of the relative forms of the several superposed webs relied upon for establishing and maintaining registration and alignment of 45 the forms, with each successive advancement of the web.

It is an object of the invention to provide 50 engaging friction rollers for engaging the webs therebetween and advance the web or webs until a perforation in the web is reached and determining the extent of the frictional feed.

Another object of the invention is to provide pin mechanism for engaging through

a registering aperture in the web for adjusting the web and the apertures thereof with relation to the frictional feeding mechanism and with respect to the forms of the several superposed webs for registration and alignment thereof and for maintaining 60 the webs in the adjusted or definite position upon a writing table in rear of the friction feeding mechanism and for holding the webs against displacement during a 65 tearing off operation of an advanced position of the webs beyond the feeding mechanism.

Other objects of the invention relate to the means for withdrawing the pins from the perforations, conducted with a web feed 70 starting, to the web feed starting mechanism, and to rewinding mechanism within the machine for one of the webs, and to novel features, combination of elements and engagement of parts hereinafter described 75 and more particularly pointed out in the claims, convenient embodiment is typically illustrated in the accompanying drawings, forming a part of the specification, in which:

Fig. 1 is a fragmentary plan of my improved mechanism.

Fig. 2 is a vertical section on line 2, 2, Fig. 1.

Fig. 3 is a side elevation, the gear casing 85 cover being removed.

Fig. 4 is a transverse section on line 4, 4, Fig. 3.

Figs. 5, 6 and 7 are respectively a plan, 90 side elevation and end view of the spring stop-pin carrying device.

Figs. 8, 9, 10, and 11 are diagrammatic views showing the action of the stop pins relative to the sheets.

Fig. 12 is a section on line 12, 12, Fig. 8. 95

Fig. 13 is a section on line 13, 13, Fig. 4.

Fig. 14 is a view similar to Fig. 13, showing a modified form.

Fig. 15 is a transverse section of the mechanism shown in Fig. 14. 100

Fig. 16 is a plan view of the sleeve showing the method of mounting the stop-pins, lever, pawl and spring thereon.

In the foregoing description it has been generally designated that the pins "intercept" the paper or strip through registering apertures, this word however is intended to define merely a stopping or arresting of the

paper for any and all functions which may be achieved by the engagement of the pins through the paper apertures.

Moreover, no endeavor has herein been made to describe in treatise-like detail, or in a thoroughly comprehensive manner, all of the accomplishments of the machine or of its various uses, and advantages relative to registration, alignment and successive advancements of the webs, or of the possibilities which may be inherent in the structure, a clear description of the details of construction and general operation of the machine only being given.

15 In the drawings, 1 designates a base. Secured to the base and upstanding therefrom in spaced parallel relation are side frames 2 and 3, which may be of sectional form, one section hingedly mounted upon the second 20 for convenient access to the interior of the frame. The side frames are provided with supports 4 for journaling the webs of paper under a proper degree of tension. Only one of these supports is shown in the drawings, 25 see Fig. 2, but as is usual the frames are provided with sufficient number of supports to journal the number of strips of paper with which the device is designed for use. A writing table 5 is secured upon and supported between the side frames, and the strips are drawn over this writing table in superposed relation. A margin frame 6 is hingedly mounted above the writing table, the paper being drawn between the writing table and 35 the margin frame. Any number of strips of paper may be used within practical limits, but I have shown three. The strips are perforated or apertured at predetermined intervals divisional of the specific sized sheet 40 blanks of which the strips are comprised, these perforations being aligned longitudinally of the direction of withdrawal. The drawings show the strips provided with two apertures aligned crosswise of the direction 45 of travel of the strips within each sheet blank, thus providing a number of series of longitudinally spaced apertures. Where several strips are used, the respective series of longitudinally spaced apertures are 50 superposed. A flat spring member 7 is fixed to the under surface of the writing table 5 and is extended forwardly from the secured portion thereof to a point adjacent the forward end of the writing table. This member is formed of two parallel spaced spring members 8 and a cross member 9 secured to said spring members at the free end thereof and extending between the same. This member is provided with one or more pins 10, 55 see Figs. 5, 6 and 7, which pins are clamped between respective members 8 and respective ends of the cross member 9 in grooves formed therein, and extend forwardly therefrom and then upwardly at right angles thereto. The number of pins depends on

the number of series of longitudinally spaced apertures in the strips, there being two shown.

Disposed upon an axis placed crosswise of the strips is a roll 11. This roll is arranged beyond the forward end of the writing table and is journaled at its ends in bearing blocks 12 mounted for vertical movement in vertical bores 13 of the respective side frames 2 and 3, the shaft of the roll extending through vertical slots communicating with the respective bores, to permit vertical movement of the roll. The roll is normally maintained in a lower position by compression springs 14 disposed in respective bores 13, above the bearing blocks 12, and abutting the bearing blocks and plugs 15, screw threaded into the upper ends of respective bores 13, with their opposite ends. See Fig. 4. Journaled in the side frames and extending between the same on an axis parallel with the axis of the roll 11 and disposed below the same is a shaft 16. The roll and shaft are rotated in unison by two meshing gears 17 disposed adjacent and on the inside of side frame 2, in Fig. 4, one of these gears being secured to the shaft of roll 11 and the other being secured to shaft 16. Trip arms 18 are rotatably mounted on the shaft 16 adjacent respective side frames, the arm adjacent the frame 2 being disposed inside of the gears 17. Endwise movement of the shaft 16 is prevented by collars 19 secured thereon adjacent to and on the inside of the frames, the collar adjacent the frame 2 being disposed on the inside of the gear 17, a trip arm 18 being disposed between said gear and said collar, and the collar adjacent the side frame 3 being disposed on the inside of the adjacent trip arm 18, said arm being between said collar and the side frame 3. End thrust of the roll 11 is prevented by outwardly facing shoulders, formed by the reduced ends of the shaft thereof, acting against the respective side frames.

The shaft 16 is provided with one or more disks 20, depending upon the number of series of longitudinally spaced apertures in the paper, there being two shown. These disks are secured upon the shaft 16 in spaced relation and are aligned with respective longitudinally spaced apertures of the paper. The disks are adapted to engage the paper between them and the roll 11 to withdraw the paper when the roll and disks are rotated in withdrawing directions, the gears 17 being so proportioned that the peripheral speeds of the disks and roll are the same.

The disks and roll provide opposing annular grooves 21, and the pins 10, there being the same number of these as there are disks and opposed grooves, for reasons now to appear, are disposed to project from grooves of the respective disks into respective opposed grooves of the roll. It is ob-

vious that the pins 10 are disposed in alignment with respective series of longitudinally spaced apertures of the paper, because of their projecting relation within said grooves.

5 The paper extends over the writing table beneath the margin frame 6 and forwardly thereof between the roll 11 and disks 20 which engage the same to withdraw it from the frame when the roll and disks are rotated. However, when apertures of the paper register with the line of contact of the roll and disks, the driving relation of the roll and disks with the paper ceases and permits further rotation of the rolls and disks without corresponding withdrawal of the paper by reason of the fact that the disks are less in width than the width of the respective apertures of the paper and are aligned therewith. The pins 10 are yieldably urged 15 against a face of the paper by the spring member 7, and are aligned with respective series of longitudinally spaced apertures, are adapted to engage through respective apertures to intercept withdrawal of the paper and are disposed to intercept such withdrawal during the registry of the engaged apertures with the line of contact of the roll and disks with the paper. By reason of the fact that the pins engage the same apertures that are in registry with the line of contact of the rolls with the paper, any shrinkage or expansion of the paper between the longitudinally spaced apertures cannot prevent the proper cooperation of the disks 25 and pins in stopping the withdrawal of the paper, nor can longitudinal misfacing of the apertures prevent such proper cooperation. It will be further noted that paper having any desired arrangement of longitudinally spaced apertures may be used. Figs. 8 to 12 show the roll, a disk, a pin, and the paper in the positions they assume while the paper is being withdrawn between the positions of interception of withdrawal thereof. Figs. 40 30 and 11 show the same parts in the position they assume when the paper is in an intercepted position and before the parts are actuated to effect further withdrawal of the paper as hereinafter described.

45 It will be noted that by reason of the grooves 21 and of the projecting relation of the pins 10 therewith, the pins may be positioned centrally of the apertures with the rearwardly facing strip-intercepting surfaces thereof in close proximity with the line of contact of the roll with the disks, thus permitting the apertures of the paper to be relatively small and circular in form as is the standard practice at present, without decreasing the size of the roll and disks.

I have shown three superposed strips and they are designated in the drawings by the reference characters 22, 23 and 24 in numerical order, the strip nearest the writing table 50 being designated as 22. The apertures of

the several strips are designated by the reference character 25.

It is sometimes the case that the respective apertures of the several strips are not in registry with each other longitudinally of the direction of withdrawal as they approach the line of contact of the roll 11 and the respective disk with the paper, as shown in Fig. 8. This is connected during the interception of the strips in the following manner. As the forwardmost aperture registers with the line of contact of the roll and the disks with the paper, the driving relation of the roll and disks with this strip is broken by reason of the fact that the disks are less in width than the apertures and are aligned therewith, and no part of the strip lies between the roll and disks to establish a withdrawing engagement therewith. See Fig. 9 in which the aperture 25 of the top strip is registered with the line of contact of the roll and disks with the paper. As the aperture of the one strip registers with the line of contact of the roll with the disks, the roll under the influence of the springs 14 moves 90 downwardly toward the disks to act upon the remaining strip or strips. This action is repeated until all the apertures of all the strips are registered with the line of contact of the roll and disks with the paper. Fig. 95 10 shows the apertures of the strips 22 and 24 registered with the line of contact of the roll and disks, with the respective aperture of the strip 23 still to be registered therewith, and Fig. 11 shows the apertures of all 100 the strips registered with the line of contact of the rolls and disks. When the apertures of all the strips are in registry with the line of contact of the roll with the disks, the pins 10, under the influence of the spring member 105 7, move through respective registering apertures of the strips and into the opposed grooves to intercept withdrawal of the paper as hereinbefore described.

By reason of the fact that the pins and disks operate with the same respective apertures during the interception of the withdrawal of the paper, the several superposed strips may have the longitudinally spaced aperture thereof spaced differently, so that the several webs are withdrawn unequally during each withdrawal thereof, thus permitting relatively short sheet blanks to comprise any of the strips relatively to the length of sheet blanks comprising any other strip. 110 This arrangement is advantageous where it is desired to record only a portion of the data, written on the sheet blanks comprising one strip, on the sheet blanks comprising another strip. The carboning device of the 115 machine may be arranged for this purpose in an obvious manner.

It is sometimes the case that the strips are slightly out of alignment crosswise of the strips as shown in Fig. 1. This is cor- 120 125 130

rected during the interception of the strips by each pin co-operating with its disk, the close proximity of the pins in central relation with the disks making such cooperation 5 very effective.

The paper as it is withdrawn over the writing table 5 is guided by inwardly facing surfaces 26 of the side frames 2 and 3, projecting above the writing table. These surfaces do not closely confine the paper and do not interfere with the withdrawal thereof or cause buckling of the paper on the writing table, but guide the paper so that the apertures thereof are within engaging range 15 of the pins 10.

After the withdrawal of the paper is intercepted, further rotation of the roll and disks cannot effect further withdrawal of the paper until the pins 10 are withdrawn 20 from the engaged apertures and the roll and disks engaged with the paper beyond the apertures. This action is effected by mechanism now to be described. Mounted for longitudinal movement upon the shaft 16 25 between the disks 20 is a roll 27. The roll 11 is annularly grooved, as designated at 28, on either side of the mid portion 29 thereof. The roll 27 is substantially the same width as the portions 29 of roll 11 and is 30 adapted to be moved into and out of line therewith opposite a groove 28 to make and break driving engagement between the roll 27 and the portion 29 of roll 11 with the paper. The shaft 16 is bored from the end 35 thereof adjacent the side frame 2, as designated at 30, see Fig. 4, and has diametrically disposed slots 31 formed therein below the mid portion 29 of roll 11. A rod 32 is mounted within the bore 30 for longitudinal 40 movement, and a pin 33 is secured in diametrically disposed holes in the roll 27 and the adjacent end of the rod and extends through slots 31, to secure the roll and rod together and to prevent rotation of the roll 45 relative to the shaft 16. The slots 31 extend longitudinally of the shaft to permit longitudinal movement of the roll and rod. Thus longitudinal actuation of the rod effects longitudinal movement of the roll 27 to make 50 and break driving engagement between roll 27 and mid portion 29 of roll 11 and the paper. Accidental movement of the rod 32 is prevented by a spring friction device 34 of usual construction mounted in an opening 55 of the rod and frictionally engaging the surface of the bore of shaft 16. The roll 27 is provided with a conical portion 35 disposed concentrically therewith. An arm member 36 is secured upon the forward end of the cross member 9 and extends forwardly therefrom below shaft 16. This arm is adapted 60 to be engaged by the cone 35 as the roll 27 is moved into paper engaging relation with the mid portion 29 of roll 11, the arm being depressed by the cone during such move-

ment, whereby the spring member 7 is depressed and the pins 10 withdrawn from the engaged apertures of the paper. Thus when the roll 27 is moved into paper engaging relation with the mid-portion 29 of the roll 70 11, rotation of the shaft 16 will effect initial withdrawal of the paper from the aperture registering position. As soon as this initial withdrawal is effected, the roll 27 may be moved out of paper engaging relation, thus allowing the pins 10, under the influence of spring member 7, to move against the face of the paper preparatory to engaging through the next successive apertures of the paper as it is withdrawn by 80 disks 20 and roll 11, as they are rotated as hereinbefore described. The shaft 16 extends outwardly beyond the side frame 2 and is conveniently rotated by a bored hand crank 37 secured by means of its bore upon 85 the extending end of the shaft.

The side frame 2 is formed with an outwardly facing gear case 38 which is closed by a cover 39 secured thereto, this cover having an aperture through which shaft 16 extends. Formed on the outer surface of the cover 39 around shaft 16 is an outwardly facing cam 40. The rod 32 extends beyond shaft 16, and a cam actuated member 41 is secured on the extending end of the rod for movement and rotation therewith, and extends radially therefrom and then inwardly beyond the path of the arm of the crank, for engagement with cam 40. The cam actuated member is additionally secured for 90 rotation with shaft 16 by engagement thereof with a longitudinal slot 42 formed on the hub of the crank. The cam actuated member is adapted to be moved by the cam outwardly, longitudinally of shaft 16, from an 95 inward position upon rotation of said shaft in its paper withdrawing direction. The roll 27 and cone member 35 are arranged so that inward movement of the rod causes the same to function and outward movement of the rod renders the same functionless. Thus it will be observed that the cam actuates the rod through member 41 to render the roll 27 and cone member 35 functionless. In effecting the movement of the paper out of an 100 intercepted position, the rod 32 is manually moved inwardly, when the relative positions of the cam 40 and cam actuated member 41 are such that the entire inward movement of the rod is permitted, this position being 105 shown in Figs. 1 and 4. Then the crank 37 is rotated in a withdrawing direction until the withdrawal of the paper is again stopped, as hereinbefore described. During such rotation of the crank, the cam 40 engages the cam actuated member 41 to move it and rod 32 outwardly to render the roll 27 and cone member 35 functionless, this 110 action taking place after the engaged apertures are moved out of aperture registering 115 120 125 130

position and prior to the registry of successive apertures with the line of contact of roll 11 and disks 20.

It will be noted that the bodily movement 5 of the roll 27 out of paper engaging relation leaves the paper entirely free, thus obviating any possibility of this roll causing interference with the paper when withdrawn by the roll 11 and disks 20 or when the withdrawal of the paper is stopped.

It will be further noted that the mechanism for controlling the longitudinal movement of the roll 27 is very simple and compact and well adapted for use in a machine in which several disks are used and the roll 27 is disposed between the same as shown.

The periphery of the roll 27 is provided with a depression or flat portion 42 to permit this roll being moved into paper engaging relation with the mid-portion 29 of roll 11 free of the paper, so that longitudinal movement of the roll into functioning position while the depression faces the paper is 25 not obstructed or interfered with by the paper, nor is any side thrust exerted on the paper which might disarrange the same. This depression is positioned relatively to the cam member 41, so that it is opposite 30 the roll 11 when the cam actuated member is positioned relatively to the cam 40, so that the entire inward movement of the rod 32 is permitted when the depression faces the paper.

35 A winding roll 43 is removably supported for rotation between the side frames 2 and 3 in a usual manner, and the lower strip 22 is wound thereon after it passes the roll 11 and disks 20, this strip being guided thereto 40 by a guide roll 44 rotatably mounted between the side frames in parallelism with shaft 16. The roll 43 is driven from shaft 16 in the following manner by a gear train disposed within the gear case formation 38. See 45 Figs. 3 and 4. A stud 45 is rotatably mounted in the side frame 2 and cover 39 and extends across the enclosure of the gear case formation in parallelism with shaft 16. Mounted for rotation on stud 45 and for 50 movement longitudinally thereof is a friction gear 46 which is meshed with a gear 47 secured upon shaft 16. A second friction gear 48 is secured on the stud 45 inwardly of gear 46 and abuts the side frame 2 to prevent inward thrust thereof. Friction disks 49 of leather or other friction material attached to the respective opposing faces of 55 the gears 46 and 48 surround the stud 45 and provide a frictional driving connection between the same, and a compression spring 60 surrounds the stud 45 between the cover 39 and gear 46 and exerts inward pressure upon gear 46 to maintain this gear and gear 48 and the interposed friction disks 49 in 65 frictional driving engagement. A gear 51,

disposed concentrically with the roll 43, is rotatably mounted in the side frame 2 and cover 39 and meshes with gear 48. This gear has a square bore therein, as has the roll 43, through which an axle 52 extends to support the roll 43, and to establish a driving connection between this roll and gear. The axle 52 has a reduced round end, journaled in a bore of the side frame 3 and is detachably retained in place by a spring arm 53 at 70 the gear end of the axle, the said spring arm being supported by the cover 39. A pawl 54 is pivotally mounted within the gear case and engages the teeth of gear 45, to prevent rotation of the mechanism in a direction 75 reversely of the withdrawing direction, this pawl being urged against the gear by a spring 55. See Fig. 3.

The gear train, driving the winding roll 43 is so proportioned that the winding roll 80 will wind up the strip 22 as it is withdrawn by the roll 11 and disks 20 when there is a minimum amount of the strip wound on the roll 43. It is obvious that as the amount of the strip wound upon the roll 43 increases 85 90 the driving mechanism will tend to wind the strip upon the roll 43 faster than it is withdrawn by the roll 11 and disks 20. When this condition arises the gears 46 and 48 slip with relation to one another, the rotation of 95 the roll 43 being retarded by the strip 22 as withdrawn by the roll 11 and disks 20.

During the interception of the withdrawal of the paper, the driving mechanism has a tendency to continue to wind the strip 100 105 22, after the apertures of the paper register with the line of contact of the roll 11 and disks 20, and sometimes interferes with the proper and uniform interception of the withdrawal of the strip. This condition is aggravated by the fact that the tension on the strip 22 is effected by the respective supports 4 and varies as the roll of the strip 22 supported thereby varies in size.

To negative to a great extent the effect of 110 this condition upon the interception of the withdrawal of the paper, and to dispense with the necessity of a delicate adjustment of the tension exerted upon the strip 22 by the supports 4 and the driving tension of 115 the driving mechanism of the roll 43, the following mechanism is provided. See Figs. 2, 4 and 13.

The stud 45 is extended inwardly of the side frame 2 and secured thereon is a ratchet 120 wheel 56, the abutment surfaces of the teeth of which face in the direction of rotation of the stud. Mounted for rotative movement upon the usual trip arm rock shaft 57, which is pivotally mounted on the side frames and extends between the same, is a sleeve 58, this sleeve being disposed between the usual trip arm engaging pins 59, secured on the rock shaft adjacent respective side frames, the inner faces of the trip 125 130

arms 18 forming stops to prevent lateral movement of the said sleeve. Secured upon the end of this sleeve adjacent the ratchet wheel 56 is a pawl 60 which is adapted to engage the abutment surface of any tooth of the ratchet wheel 56 to prevent rotation of the stud 45 in the direction of rotation thereof, and consequently rotation of the roll 43 in its winding direction as rotated by the driving mechanism. Formed from the sleeve 58 and extending radially therefrom in alignment with the arm member 36, hereinbefore described, is an arm 61. The arm member 36 extends forwardly of the cone 35 and is offset downwardly so that its forward end underlies arm 61. An angle piece 62 is secured to the forward end of the arm member 36 and overlies such forward end and the arm 61; thus confining the arm 61 between it and the forward end of arm member 36 to effect pivotal movement of the sleeve 58 and pawl 60 in correspondence with the movement of arm member 36.

As hereinbefore described, the arm 36 is moved downwardly by the cone 35 to depress the spring member 7 and to withdraw the pins 10 from the engaged apertures of the paper when the cone is moved longitudinally in the one direction, and when the cone is moved in the opposite direction, the spring member moves the pins 10 upwardly against a face of the paper and through registering apertures thereof, the arm member 36 being moved upwardly by the spring member during this movement. Downward movement of the arm member 36 operates to move the pawl 60 out of engaging relation with ratchet wheel 56, the parts being so arranged that when the pins 10 are in the position they assume when urged against a face of the paper, the pawl is positioned out of engaging relation with the ratchet wheel, thus permitting rotation of the winding roll 43, when the pins are urged by the spring member 7 to engage through registering apertures of the paper. The upward movement of the arm 36, from the position it is in when the pins are in their paper opening engaging position, operates to move the pawl 60 into engagement with the ratchet wheel to engage a tooth thereof and to stop rotation of the roll 43 during further rotation of shaft 16, thus preventing any withdrawing tension being exerted upon the strip 22 after the pins 10 have engaged through registering apertures of the paper. As the roll 27 and cone 35 are moved to effect initial movement of the paper out of aperture registering position, the pawl 60 is moved out of engagement with the ratchet wheel, but movement of the roll 27 and cone 35 back to functionless position by the cam 40 does not reengage this pawl with the ratchet wheel, as the engagement of the pins

10 with the face of the paper prevents the entire upward movement of the pins until apertures of the strip register with the pins to permit the completion of the upward movement thereof. Thus it will be observed that the mechanism for interrupting the driving of the roll 43 acts in an automatic manner with the usual operation of the device and does not require additional attention.

A tearing-blade 63 is secured to and extends across between the frames 2 and 3 and is formed around the roll 11 to afford a cover therefor. See Figs. 2 and 3. The tearing-blade is provided with a forwardly facing tearing edge 64 by means of which the withdrawn portion of any or all of the strips can be severed from the remainder thereof. The forward end of the enclosure of the side frames is closed by a hinged cover 65 detachably secured in place to permit access to the roll 43, the upper portion of the cover guiding the upper strips above the same forwardly in an accessible position for manual grasp.

In the modification shown in Figs. 14, 15 and 16, a sleeve 64^a is pivotally mounted on the trip arm rock shaft 57 between the trip arm engaging pins 59, hereinbefore described. Secured upon this sleeve in spaced relation are arms 65^a, which extend rearwardly below shaft 16 and turn upwardly at the rear of said shaft so that their free ends 66, forming paper engaging pins, are disposed in projecting relation with the grooves 21 of respective disks 20 in a manner similar to the projecting relation that the pins 10, hereinbefore described, have with grooves 21, as hereinbefore described.

A helical torsional spring 67 encircles the sleeve 64^a at its end adjacent the side frame 3 and has its one end secured to the adjacent arm 65^a and has its other end secured to the pin 59 to rotate the sleeve 64^a clockwise, in Fig. 15, to move the pins 66 upwardly to project from grooves 21 of disks 20 through registering apertures of the paper and into the respective opposite grooves 21 of roll 11, this mechanism functioning similarly to that of the spring member 7 and pins 10, hereinbefore described. An arm 68 is secured on the sleeve 64^a between arms 65^a and extends rearwardly below shaft 16 and is acted upon by the cone 35 of roll 27 to move the pins 66 out of engagement with apertures of the paper when the roll 27 is moved into functioning position, as hereinbefore described. A pawl 69 is secured on the sleeve 64^a adjacent the frame 2 and is disposed to be moved into and out of engagement with the ratchet wheel 56, with the movement of the pins 66 into and out of engagement with apertures of the paper in a manner similar to the construction hereinbefore described, the cone

35 of roll 27 operating to disengage the pawl 69 as it disengages the pins 66 from the apertures of the paper. The remainder of the modification is the same as the construction heretofore described, and the operation of both constructions are similar, in view of which a detailed description of the same is deemed unnecessary.

Having described my invention, I claim—

10 1. A device of the nature described including a frame from which a strip of paper is withdrawn, the strip having spaced apertures aligned longitudinally with its direction of withdrawal, a rotatably mounted roll 15 disposed opposite one face of the strip and disposed on an axis crosswise of the strip, a rotatably mounted disk element disposed on an axis crosswise of the strip and disposed opposite the other face of the strip and with said roll 20 to exert pressure upon the strip disposed between it and the roll to withdraw the strip when the roll and disk elements are rotated in withdrawing directions, said disk element having a width less than the width of said 25 apertures and disposed in alignment therewith, said disk and roll having opposed annular grooves disposed centrally at the disk element and of width less than the width of the same, and an abutment member yieldably urged toward a face of the strip and across the path thereof and disposed to project from one of the said grooves and to engage through a registering aperture of the strip and into the other groove to intercept 30 withdrawal of the strip and disposed to intercept such withdrawal during the registry of the engaged aperture with the plane of the axis of said roll and disk element.

2. A device of the nature described including a frame from which a strip of paper is withdrawn, the strip having apertures spaced longitudinally and in series crosswise of the direction of withdrawal, a rotatably mounted roll disposed opposite one face of the strip and disposed correspondingly crosswise of the strip, rotatably mounted disk elements spaced crosswise of the strip and disposed on an axis correspondingly crosswise of the strip and disposed opposite the other face of the strip and with said roll to exert pressure upon the strip disposed between them and the roll to withdraw the strip when the roll and disk elements are rotated in withdrawing directions, said disk elements being disposed in alignment with respective longitudinally spaced apertures and having widths less than the widths of respective apertures, said roll and disk elements having opposed annular grooves disposed centrally of respective disk elements, said grooves being less in width than the disk elements, and abutment members spaced correspondingly crosswise of the strip in alignment with respective longitudinally spaced apertures and yieldingly urged toward a

face of the strip and across the path thereof and disposed to project from respective grooves and to engage through respective registering apertures of the strip and into the opposite grooves to intercept withdrawal of the strip and disposed to intercept such withdrawal during the registry of the engaged apertures with the plane of the axis of said roll and disk elements.

3. A device of the nature described including a frame from which several strips of paper are withdrawn in superposed relation, each strip having apertures spaced longitudinally and in series crosswise of the direction of withdrawal, the respective portions of the strips having the longitudinally spaced apertures therein being superposed, a rotatably mounted roll engaging an outer face of the strip and disposed correspondingly crosswise of the strips, rotatably mounted disk elements spaced crosswise of the strips and disposed on an axis correspondingly crosswise of the strip and disposed to engage the strips between them and the roll to withdraw the strips when the roll and disk elements are rotated in withdrawing directions, resilient means urging said roll and disk elements toward each other in the plane of the axis thereof against the strips, said disk elements being disposed in alignment with respective longitudinally spaced apertures and having widths less than the widths of respective apertures, said roll and disk elements having opposed annular grooves disposed centrally of said disk elements, said grooves being less in width than the disk elements, and abutment members spaced correspondingly crosswise of the strip in alignment with respective longitudinally spaced apertures and yieldingly urged against an outer face of the strips and disposed to project from respective grooves and to engage through respective registering apertures of the strips and into the opposite grooves to intercept withdrawal of the strips and disposed to intercept such withdrawal during the registry of the engaged apertures with the line of contact of said roll and disk elements with the strips.

4. A device of the nature described including a frame from which a strip of paper is withdrawn, the strip having spaced apertures aligned longitudinally with its direction of withdrawal, a rotatably mounted roll disposed opposite one face of the strip and disposed on an axis crosswise of the strip, a rotatably mounted disk element disposed on an axis crosswise of the strip and disposed opposite the other face of the strip and with said roll to exert pressure upon the strip disposed between it and the roll to withdraw the strip when the roll and disk elements are rotated in withdrawing directions, said disk elements having a width less than the width of said apertures and dis-

posed in alignment therewith, means for effecting initial movement of the strip out of positions in which an aperture registers with the plane of the axis of said roll and disk 5 elements including a rotatable roll disposed on an axis crosswise of the strip and rotating with said roll and disk elements and bodily movable longitudinally of its axis into and out of withdrawing relation with 10 the strip, said last mentioned roll having a depression in its periphery to permit longitudinal movement thereof free of withdrawing relation with the strip, and mechanism for moving said last mentioned roll out of 15 withdrawing relation with the strip including a cam member and a cam actuated member, said cam and cam actuated members being relatively moved with rotation of said first mentioned roll and disk element and 20 timed with relation to said depression to permit complete movement of said last mentioned roll into withdrawing relation with the strip when said depression faces the strip.

25 5. A device of the nature described including a frame from which a strip of paper is withdrawn, the strip having spaced apertures aligned longitudinally with its direction of withdrawal, a rotatably mounted roll disposed opposite one face of the strip and disposed on an axis crosswise of the strip, a rotatably mounted disk element disposed on an axis crosswise of the strip and disposed opposite the other face of the strip 35 and with said roll to exert upon the strip disposed between it and the roll to withdraw the strip when the roll and disk elements are rotated in withdrawing directions, said disk element having a width less than the width 40 of said apertures and disposed in alignment therewith, an abutment member yieldingly urged toward a face of the strip and across the path thereof and disposed to engage through a registering aperture of the strip 45 to intercept withdrawal thereof and disposed to intercept such withdrawal during the registry of an aperture with the plane of the axis of said roll and disk element, means for effecting initial movement of the strip 50 out of aperture registering position including a rotatable roll disposed on an axis crosswise of the strip and rotating with said roll and disk element and bodily movable longitudinally of its axis out of and into withdrawing relation with said strip and means 55 whereby movement of said last mentioned roll into withdrawing relation with the strip operates to withdraw said abutment member from the engaged aperture and whereby movement of this roll out of withdrawing relation with the strip operates to permit the abutment member to engage with an aperture of the strip.

60 6. A device of the nature described including a frame from which a strip of paper is

withdrawn, the strip having spaced apertures aligned longitudinally with its direction of withdrawal, a rotatably mounted roll disposed opposite one face of the strip and disposed on an axis crosswise of the strip, a 70 rotatably mounted disk element disposed on an axis crosswise of the strip and with said roll to exert pressure upon the strip disposed between it and the roll to withdraw the strip when the roll and disk elements are 75 rotated in withdrawing directions, said disk element having a width less than the width of said apertures and disposed in alignment therewith, an abutment member yieldingly urged toward a face of the strip and across 80 the path thereof and disposed to engage through a registering aperture of the strip to intercept withdrawal thereof and disposed to intercept such withdrawal during the registry of an aperture with the plane of the 85 axis of said roll and disk element, means for effecting initial movement of the strip out of aperture registering position including a rotatable roll disposed on an axis crosswise of the strip and rotating with said first 90 mentioned roll and disk element and bodily movable out of and into withdrawing relation with the strip and means whereby movement of said last mentioned roll into withdrawing relation with the strip operates to 95 withdraw said abutment member from the engaged aperture and whereby movement of this roll out of withdrawing relation with the strip operates to permit the abutment member to engage with an aperture of the 100 strip.

7. A device of the nature described including a frame from which a strip of paper is withdrawn, the strip having spaced apertures aligned longitudinally with its direction of withdrawal, a rotatably mounted roll disposed opposite one face of the strip and disposed on an axis crosswise of the strip, a rotatably mounted disk element disposed on an axis crosswise of the strip and disposed opposite the other face of the strip and with said roll to exert pressure upon the strip disposed between it and the roll to withdraw the strip when the roll and disk 110 elements are rotated in withdrawing directions, said disk element having a width less than the width of said apertures and disposed in alignment therewith, an abutment member yieldingly urged toward a face of the strip and across the path thereof and disposed to engage through a registering aperture of the strip to intercept withdrawal thereof and disposed to intercept such withdrawal during the registry of an aperture with the plane of the axis of said roll and disk element, means for effecting initial movement of the strip out of aperture registering position including a rotatable roll disposed on an axis crosswise of the strip and rotating 115 with said first mentioned roll and disk ele- 120

- ment and movable longitudinally of its axis out of and into withdrawing relation with the strip, and means including a concentric conical formation on said last mentioned 5 roll operation with conical formation on said last mentioned roll operating with the movement of this roll into withdrawing relation with the strip to withdraw said abutment member from the engaged aperture and operating with the movement of this roll out of withdrawing relation with the strip to permit the abutment member to engage an aperture of the strip.
8. A device of the nature described including a frame from which a strip of paper is withdrawn, the strip having spaced apertures aligned longitudinally with its direction of withdrawal, a rotatably mounted roll disposed opposite one face of the strip, a 15 rotatably mounted disk element disposed on an axis crosswise of the strip and with said roll to exert pressure upon the strip disposed between it and the roll to withdraw the strip when the roll and disk elements are 20 rotated in withdrawing directions, said disk element having a width less than the width of said apertures and disposed in alignment therewith, an abutment member yieldingly urged toward a face of the strip and across 25 the path thereof and disposed to engage through a registering aperture of the strip to intercept withdrawal thereof and disposed to intercept such withdrawal during 30 the registry of an aperture with the plane 35 of the axis of said roll and disk element, means for effecting initial movement of the strip out of aperture registering position including a rotatable roll disposed on an axis crosswise of the strip and rotating with said 40 first mentioned roll and disk element and bodily movable out of and into withdrawing relation with the strip, said last mentioned roll having a depression in its periphery to permit longitudinal movement thereof free of the strip, and means whereby movement of said last 45 mentioned roll into withdrawing relation with the strip operates to withdraw said abutment member from the engaged aperture and whereby movement of this roll out of withdrawing engagement relation with the strip operates to permit the abutment member to engage with an aperture of the strip.
- 55 9. A device of the nature described including a frame from which a strip of paper is withdrawn, the strip having spaced apertures aligned longitudinally with its direction of withdrawal, a rotatably mounted roll disposed opposite one face of the strip and disposed on an axis crosswise of the strip, a rotatably mounted disk element disposed on an axis crosswise of the strip and disposed opposite the other face of the strip and with said roll to exert pressure upon the strip.
- 60 10. A device of the nature described including a frame from which a strip of paper is withdrawn, the strip having apertures spaced longitudinally and in series crosswise of the direction of withdrawal, a rotatably mounted roll disposed opposite one face of the strip and disposed correspondingly crosswise of the strip, a rotatably mounted bored shaft disposed on an axis correspondingly crosswise of the strip and disposed opposite the other face of the strip, disk elements 65 spaced crosswise of the strip and secured on said shaft and adapted with said roll to exert pressure upon the strip disposed between them and the roll to withdraw the strip when the roll and shaft are rotated in withdrawing directions, said disk elements being disposed in alignment with respective longitudinally spaced apertures and having widths less than the widths of respective apertures, a rotatable roll mounted for longitudinal movement on said shaft between disk elements and rotating with said shaft and adapted with said first mentioned roll to exert pressure upon the strip disposed between it and said first mentioned roll to withdraw 70 the strip when said first mentioned roll and said shaft are rotated, said first mentioned roll having an annular depression between disk elements adjacent said second mentioned roll, said second mentioned roll being 75 80 85 90 95 100 105 110 115 120 125 130

- movable longitudinally of the shaft into alignment with said depression to break withdrawing relation with the strip, said shaft having a longitudinally extending radial opening adjacent said second mentioned roll and communicating with the bore thereof, a control rod mounted for longitudinal movement within the bore of said shaft, and a connection between said second mentioned roll and said rod extending through said radial opening and adapted to cause longitudinal actuation of said second mentioned roll upon longitudinal actuation of said rod.
15. 11. A device of the nature described including a frame from which a strip of paper is withdrawn, the strip having apertures spaced longitudinally and in series crosswise of the direction of withdrawal, a rotatably mounted roll disposed opposite one face of the strip and disposed correspondingly crosswise of the strip, rotatably mounted disk elements spaced crosswise of the strip and disposed on an axis correspondingly crosswise of the strip and disposed opposite the other face of the strip and with said roll to exert pressure upon the strip disposed between them and the roll to withdraw the strip when the roll and disk elements are rotated in withdrawing directions, said disk elements being disposed in alignment with respective longitudinally spaced apertures and having widths less than the widths of respective apertures, and a rotatable roll disposed between disk elements and coaxial therewith and rotatable with said disk elements and adapted with said first mentioned roll to exert pressure upon the strip disposed between it and said first mentioned roll to withdraw the strip when the rolls and disk elements are rotated, said first mentioned roll having an annular depression between disk elements and adjacent said roll, said second mentioned roll being movable longitudinally of its axis into alignment with said depression, a disk element on one side of said second mentioned roll being coaxially bored, a hand crank for rotating said rolls and disk elements and disposed coaxially with said disk elements and on the side of said bored disk element opposite said second mentioned roll and open at its axis, a control rod disposed coaxial with said disk elements and extending through said bored disk and outwardly therefrom beyond the path of the arm of the crank and adapted for longitudinal movement to actuate said second mentioned roll longitudinally of its axis, a cam actuated member mounted on the outwardly extending end of said rod to move longitudinally therewith and extending radially therefrom and then inwardly beyond the path of the arm of the crank and rotating with said crank, and a cam disposed inwardly of the path of the arm of the crank and engageable with said cam actuated member to move the control rod to move said second mentioned roll out of withdrawing relation with the strip when the crank is rotated in a withdrawing direction.
12. A device of the nature described including a frame from which a strip of paper is withdrawn, the strip having apertures spaced longitudinally and in series crosswise of the direction of withdrawal, a rotatably mounted roll disposed opposite one face of the strip and disposed correspondingly crosswise of the strip, rotatably mounted disk elements spaced crosswise of the strip and disposed on an axis correspondingly crosswise of the strip and disposed opposite the other face of the strip and with said roll to exert pressure upon the strip disposed between them and the roll to withdraw the strip when the roll and disk elements are rotated in withdrawing directions, said disk elements being disposed in alignment with respective longitudinally spaced apertures and having widths less than the widths of respective apertures, abutment members spaced correspondingly crosswise of the strip in alignment with respective longitudinally spaced apertures and yieldingly urged toward a face of the strip and across the path thereof and disposed to engage through registering apertures of the strip to intercept withdrawal thereof and disposed to intercept such withdrawal during the registry of apertures with the plane of the axis of said roll and disk elements, a rotatable roll disposed between disk elements on an axis crosswise of the strip and rotating with said first mentioned roll and the disk elements and disposed with said first mentioned roll to exert pressure upon the strip disposed between it and said first mentioned roll to withdraw the strip out of aperture registering position when the rolls and disk elements are rotated in withdrawing directions, said last mentioned roll being bodily movable out of and into withdrawing relation with the strip and first mentioned roll, and means whereby movement of said last mentioned roll into withdrawing relation with the strip and first mentioned roll operates to withdraw said abutment members from the engaged apertures and whereby movement of this roll out of withdrawing relation with the strip operates to permit the abutment members to engage with successive apertures of the strip.
13. A device of the nature described including a frame from which a strip of paper is withdrawn, the strip having apertures spaced longitudinally of its direction of withdrawal, a rotatably mounted roll disposed opposite one face of the strip and disposed correspondingly crosswise of the strip, rotatably mounted disk elements

- spaced crosswise of the strip and disposed on an axis correspondingly crosswise of the strip and disposed opposite the other face of the strip and with said roll to exert pressure upon the strip disposed between them and the roll, to withdraw the strip when the roll and disk elements are rotated in withdrawing directions, said disk elements being disposed in alignment with respective 5 longitudinally spaced apertures and having widths less than the widths of respective apertures, abutment members spaced correspondingly crosswise of the strip in alignment with respective longitudinally spaced 10 apertures and yieldingly urged toward a face of the strip and across the path thereof and disposed to engage through registering apertures of the strip to intercept withdrawal thereof and disposed to intercept such withdrawal during the registry of apertures with the plane of the axis of said roll and disk elements, a rotatable roll disposed between disk elements and coaxially therewith and rotatable with said disk elements and adapted with said first mentioned roll to exert pressure upon the strip disposed between it and said first mentioned roll to withdraw the strip out of aperture registering position when the rolls and disk 20 elements are rotated, said first mentioned roll having an annular depression disposed between disk elements adjacent said second mentioned roll, said second mentioned roll being movable longitudinally of its axis 25 into alignment with said depression to break withdrawing relation with the strip, and means whereby movement of said last mentioned roll into withdrawing relation with the strip and first mentioned roll operates 30 to withdraw said abutment members from the engaged apertures and whereby movement of said last mentioned roll out of withdrawing relation with the strip and first mentioned roll operates to permit the 35 abutment members to engage with successive apertures of the strip.
14. A device of the nature described including a frame from which a strip of paper is withdrawn, the strip having spaced apertures aligned longitudinally with its direction of withdrawal, means for withdrawing the strip including a rotatably mounted roll and an opposing rotatably mounted disk element, said disk element being less in width than the apertures of the strip, and aligned therewith to cause cessation of the withdrawing relation of the feeding means with the strip when an aperture registers with the plane of the axis 50 of said roll and disk element, an abutment member yieldingly urged toward a face of the strip and across the path thereof and disposed in alignment with said apertures and disposed to engage through a registering aperture in the strip to intercept withdrawal thereof and adapted to intercept such withdrawal during the registry of an aperture with the plane of the axis of said roll and disk element, a winding roll upon which the strip is wound after it passes said feeding means, a yielding frictional driving mechanism for driving the winding roll with the rotation of said roll and disk element, and means for rendering said mechanism functionless to drive the winding roll including a connection with said abutment member, adapted to be operated by the movement of said abutment member through a registering aperture to render said driving mechanism functionless. 55
15. A device of the nature described including a frame from which a strip of paper is withdrawn, the strip having spaced apertures aligned longitudinally of its direction of withdrawal, means for withdrawing the strip including a rotatably mounted roll and opposing rotatably mounted disk element, said disk element being less in width than the apertures of the strip and aligned therewith to cause cessation of the withdrawing relation of the feeding means with the strip when an aperture registers with the plane of the axis of said roll and disk element, an abutment member yieldingly urged toward a face of the disk and across the path thereof and disposed in alignment with said apertures and disposed to engage through a registering aperture in the strip to intercept withdrawal thereof and adapted to intercept such withdrawal during the registry of an aperture with the plane of the axis of said roll and disk element, a winding roll upon which the strip is wound after it passes said feeding means, a yielding frictional driving mechanism for driving the winding roll with the rotation of said roll and disk element, and means for rendering said mechanism functionless to drive the winding roll including a ratchet wheel, a movably mounted pawl adapted to be moved into and out of engagement with the ratchet wheel, and a connection between said pawl and said abutment member to move said pawl into engagement with the ratchet wheel with the movement of said abutment member into an aperture of the strip. 60
16. A device of the nature described including a frame from which a strip of paper is withdrawn, the strip having spaced apertures aligned longitudinally with its direction of withdrawal, means for withdrawing the strip including a rotatably mounted roll and an opposing rotatably mounted disk element, said disk element being less in width than the apertures of the strip and aligned therewith to cause cessation of the withdrawing relation of the feeding means with the strip when an aperture registers with the plane of the axis of said roll and disk element, a winding roll upon which the strip is wound after it passes said feeding means, a yielding frictional driving mechanism for driving the winding roll with the rotation of said roll and disk element, and means for rendering said mechanism functionless to drive the winding roll including a ratchet wheel, a movably mounted pawl adapted to be moved into and out of engagement with the ratchet wheel, and a connection between said pawl and said abutment member to move said pawl into engagement with the ratchet wheel with the movement of said abutment member into an aperture of the strip. 65

- element, an abutment member yieldingly urged toward a face of the strip and across the path thereof and disposed in alignment with said apertures and disposed to engage through a registering aperture in the strip to intercept withdrawal thereof and adapted to intercept such withdrawal during the registry of an aperture with the plane of the axis of said roll and disk element, a winding roll upon which the strip is wound after it passes said feeding means, a yielding frictional driving mechanism for driving the winding roll with the rotation of said feeding means, means for rendering said mechanism functionless to drive the winding roll including a connection with said abutment member, adapted to be operated by the movement of said abutment member through a registering aperture to render said driving mechanism functionless, and means for initiating movement of the strip out of aperture registering position during further rotation of said roll and disk element including a movable member controlling the functioning of the same, said movable member operating to withdraw said abutment member from the engaged aperture and to render said second mentioned means functionless when moved to functioning position.
17. A device of the nature described, including a frame from which a strip of paper is withdrawn, the strip having spaced apertures aligned longitudinally of its direction of withdrawal, means for withdrawing the strip including a rotatably mounted roll and an opposing rotatably mounted disk element, said disk element being less in width than the apertures of the strip and aligned therewith to cause cessation of the withdrawing relation of the feeding means with the strip when an aperture registers with the plane of the axes of said roll and disk element, an abutment member yieldingly urged toward a face of the strip and across the path thereof and disposed in alignment with said aperture and disposed to engage through a registering aperture of the strip to intercept the withdrawal thereof and adapted to intercept such withdrawal during the registry of an aperture with the plane of the axes of said roll and disk element, a winding roll upon which the strip is wound after it passes said feeding means, a yielding frictional driving mechanism for driving the winding roll with the rotation of said roll and disk element, means for rendering said mechanism functionless to drive the winding roll including a connection with said abutment member, adapted to be operated by movement of said abutment member through a registering aperture to render said driving mechanism functionless and adapted to be operated by movement of said abutment member out of engagement with an aperture to render said means functionless, means for initiating movement of the strip out of aperture registering position during further rotation of said roll and disk element including a movable member controlling the functioning of the same, said movable member operating to withdraw said abutment member from the engaged aperture and to render said second mentioned means functionless when it is moved into functioning position, and means for moving said movable member into non-functioning position including a cam and a cam actuated member, said cam and cam actuated members being relatively moved by rotation of said roll and disk element.
18. A device of the nature described including a frame from which a strip of paper is withdrawn, the strip having spaced apertures aligned longitudinally of its direction of withdrawal, means for withdrawing the strip including a rotatably mounted roll and an opposing rotatably mounted disk element, said disk element being less in width than the apertures of the strip and aligned therewith to cause cessation of the withdrawing relation of the feeding means with the strip when an aperture registers with the plane of the axes of said roll and disk element, an abutment member yieldingly urged toward a face of the strip and across the path thereof and disposed in alignment with said apertures and disposed to engage through a registering aperture of the strip to intercept the withdrawal thereof and adapted to intercept such withdrawal during the registry of an aperture with the plane of the axes of said roll and disk element, a winding roll upon which the strip is wound after it passes said feeding means, a yielding frictional driving mechanism for driving the winding roll with the rotation of said roll and disk element, means for rendering said mechanism functionless to drive the winding roll including a connection with said abutment member, adapted to be operated by movement of said abutment member through a registering aperture to render said driving mechanism functionless and adapted to be operated by movement of said abutment member out of engagement with an aperture to render said means functionless, means for initiating movement of the strip out of aperture registering position during further rotation of said roll and disk element including a movable member controlling the functioning of the same, said movable member operating to withdraw said abutment member from the engaged aperture and to render said second mentioned means functionless when it is moved into functioning position, and means for moving said movable member into non-functioning position including a cam and a cam actuated member, said cam and cam actuated members being relatively moved by rotation of said roll and disk element.
19. A device of the nature described including a frame from which a strip of paper is withdrawn, the strip having apertures spaced longitudinally and in series cross-wise of its direction of withdrawal, means for withdrawing the strip including a ro-

tatably mounted roll and opposing rotatably mounted disks spaced crosswise of the strip, said disks being less in width than the apertures of the strip and aligned with respective longitudinally spaced apertures to cause cessation of the withdrawing relation of the feeding means with the strip when apertures register with the plane of the axes of said roll and disk elements, abutment members yieldably urged toward a face of the strip and across the path thereof and disposed in alignment with respective longitudinally spaced apertures and disposed to engage through respective registering apertures of the strip to intercept the withdrawal thereof and adapted to intercept such withdrawal during the registry of apertures with the plane of the axes of said roll and disk elements, a winding roll upon which the strip is wound after it passes said feeding means, a yielding frictional driving mechanism for driving the winding roll with the rotation of said roll and disk elements, and means for rendering said mechanism functionless to drive the winding roll including a connection with said abutment member adapted to be operated by the movement of said abutment members through registering apertures to render said driving mechanism functionless.

20. A device of the nature described including a frame from which a strip of paper is withdrawn, the strip having apertures spaced longitudinally and in series crosswise of its direction of withdrawal, means for withdrawing the strip including a rotatably mounted roll and opposing rotatably mounted disk elements spaced crosswise of the strip, said disk elements being less in width than the apertures of the strip and aligned with respective longitudinally spaced apertures to cause cessation of the withdrawing relation of the feeding means with the strip when apertures register with the plane of the axes of said roll and disk elements, abutment members yieldingly urged toward a face of the strip and across the path thereof and disposed in alignment with respective longitudinally spaced apertures and disposed to engage through respective registering apertures of the strip to intercept the withdrawal thereof and adapted to intercept such withdrawal during the registry of apertures with the plane of the axes of said roll and disk elements, a winding roll upon which the strip is wound after it passes said feeding means, a yielding frictional driving mechanism for driving the winding roll with the rotation of said roll and disk elements, means for rendering said mechanism functionless to drive the winding roll including a connection with said abutment members through registering apertures to render said driving mechanism functionless, and means for initiating movement of

the strip out of aperture registering position during further rotation of said roll and disk elements including a movable member controlling the functioning of the same, said movable member operating to withdraw said abutment members from the engaged apertures and to render said second mentioned means functionless when moved to functioning position. 70

21. A device of the nature described including a frame from which a strip of paper is withdrawn, the strip having apertures spaced longitudinally of its direction of withdrawal, means for withdrawing the strip including a rotatably mounted roll and an opposing rotatably mounted disk, said disk being less in width than the apertures of the strip and aligned with said apertures to cause cessation of the withdrawing relation of the feeding means with the strip when an aperture registers with the plane of the axes of said roll and disk elements, a pivotally mounted pin adapted to move toward a face of the strip and across the path of the same and disposed in alignment with respective longitudinally spaced apertures and adapted to engage through a registering aperture of the strip to intercept the withdrawal thereof and disposed to intercept such withdrawal during the registry of an aperture with the plane of the axes of said roll and disk element, a spring yieldably urging said pin toward the face of the strip and across the path of the same, a winding roll upon which the strip is wound after it passes said feeding means, a yielding frictional driving mechanism for driving the winding roll with the rotation of said roll and disk element, and means for rendering said mechanism functionless to drive the winding roll including a member pivoted coaxially with said pin and secured therewith and adapted to be moved to render said driving mechanism functionless with the movement at said pin into engagement with an aperture of the strip.

22. A device of the nature described including a frame from which a strip of paper is withdrawn, the strip having apertures spaced longitudinally and in series crosswise of its direction of withdrawal, means for withdrawing the strip including a rotatably mounted roll and opposing rotatably mounted disk elements spaced crosswise of the strip, said disk elements being less in width than the apertures of the strip and aligned with respective longitudinally spaced apertures to cause cessation of the withdrawing relation of the feeding means with the strip when apertures register with the plane of the axes of said roll and disk elements, a pivotally mounted shaft element disposed on an axis crosswise of the strip, pins secured to said shaft element in spaced relation and adapted to move toward 115
120
125
130

a face of the strip and across the path of the same, and disposed in alignment with respective longitudinally spaced apertures and adapted to engage through a registering aperture of the strip to intercept and disposed to intercept such withdrawal during the registry of apertures with the plane of the axes of said roll and disk elements, a spring yieldably urging said pins toward the 10 face of the strip and across the path of the same, a winding roll upon which the strip is wound after it passes said feeding means, a yielding frictional driving mechanism for driving the winding roll with the rotation of said roll and disk elements, and means 15

for rendering said mechanism functionless to drive the winding roll including a member secured to said shaft element and adapted to be moved to render said driving mechanism functionless with the movement of 20 said pins into engagement with the apertures of the strip.

In witness whereof, I hereunto subscribe my name, as attested by the two subscribing witnesses.
